United States Patent Office.

MOSES P. WALTON, OF MARLBORO, OHIO.

Letters Patent No. 71,556, dated November 26, 1867.

IMPROVED WASHING-MACHINE.

The Schedule referred to in these Letters Patent and making part of the same.

TO ALL WHOM IT MAY CONCERN:

Be it known that I, MOSES P. WALTON, of Marlboro, in the county of Stark, and State of Ohio, have invented new and useful Improvements in Washing-Machines; and I do hereby declare that the following is a full, clear, and exact description of my invention, reference being had to the accompanying drawings, and to the letters of reference marked thereon, of which drawings—

Figure 1 is a side view of a machine with my improvements.

Figure 2 is a plan of the same.

Figure 3 is an end view of the same.

Figure 4 is a side view of the connecting-rod.

Figure 5 is a plan of the same, part being shown in full, and part in section.

Figures 6, 7, 8, and 9 are elevations and plans of several devices for connecting the crank and connecting-rod.

The nature of my invention consists in a peculiar arrangement of a fly-wheel, crank, and connecting-rod, with a crank on the shaft of a washing-machine of that class where the washing is performed by means of the partial and reciprocating motion of a beater, by means of which I cause a rotation of the fly-wheel to produce the desired motion of the beater, thus lessening the labor of the working of said beater, and greatly increasing the utility of the machine.

To enable others skilled in the art to make and use my invention, I will proceed to describe its construction and operation.

A is the main box of the machine, supported on legs, as shown, and which serves to hold the water and clothes to be washed. The cover B is hinged to one side of the box A by means of hinges *a a'*. C is the axle of the beater G, said beater G being made of two arms, crossing each other at right angles, and having the pins at their ends, as shown, the pins serving to stir the clothes in the water, or in any other suitable manner whereby a beater of this class is produced. An arm, L, is secured to the cover B, as shown, and at the end of said arm is arranged the shaft I, on which is the fly-wheel J and the crank H. A crank, D, is made on the top of the beater-shaft C, and this crank is connected to the crank H by means of connecting-rod F. This connecting-rod F, shown in detail in figs. 4 and 5, has a cylinder, E, arranged in one end, and a slotted hole, b, indicated by dotted lines in figs. 1 and 4, and seen in plan in fig. 5.

The crank D is passed through the hole b and a hole in the cylinder E, the object of the cylinder E and hole b being to allow of both a horizontal and vertical motion to the connecting-rod F without binding on the crank D. A hole, c, of the form shown in side view and section, is made in the other end of the connecting-rod F, the object of such shape for said hole being to allow the connecting-rod F to conform to the motion of the crank D without binding on the crank H.

Two parts of cylinders d d, shown in fig. 6, may be used in a suitably-formed hole in the connecting-rod F, by putting in these two pieces d d, and then inserting the crank D or H, which holds them in the rod F, or a crank-arbor, C, shown in fig. 7, may be inserted in the rod F, and have the crank D or H attached to it, as shown, or a crank-arbor, g, may be inserted in the rod F, as shown in fig. 8, and arranged with reference to the connecting-rod F, and crank D or H, as there shown, either of these last three devices serving to allow of the peculiar motion of the connecting-rod F without binding or cramping on the crank D or H.

Another device, shown in fig. 9, where the connecting-rod, shown at N, is made of an iron rod, bent as shown, may be used. A block, h, having the crank D or H inserted in it, and also the end of the connecting-rod H—the last being inserted at right angles to the first—is sometimes a useful mode of connecting the crank D or H, especially in a very compact machine, where said cranks might be brought near together. A metallic boxing, with surfaces arranged like the hole c, may also be used in connection with the crank H.

It is readily seen that, by rotating the fly-wheel J, by means of the handle K, a reciprocating rotary motion of the beater G is effected, by which the washing of the clothes in the tub or box A is effected. The arm L, on the end of which is secured the shaft I, with fly-wheel J, is made of such length as that the weight of the shaft, fly-wheel, and their connections shall nearly balance that of the beater G, cover B, and their connections; thus making the cover B, with its connections, turn up readily on the hinges *a a'*. When the cover B is thrown back,

as indicated by dotted red lines at B, the end of the arm L strikes against the side of the box A, and thus supports the cover in position B, as shown.

Having thus fully described my invention, I wish it understood that I do not claim the box A, beater G shaft C, cover B, nor any of the devices shown in figs. 6, 7, 8, and 9, nor the cylinder E, nor hole e, taken separately, as my invention; nor do I claim the hinging of the cover B to the box, as these features have been before used; but

What I do claim as my invention, and desire to secure by Letters Patent, is—

The shaft I, with crank H and fly-wheel J, and the connecting-rod F, when used in connection with the crank D, on shaft C of beater G, substantially in the manner and for the purpose herein specified.

As evidence that I claim the foregoing, I have hereunto set my hand in presence of two witnesses.

MOSES P. WALTON.

Witnesses:

F. LYNDE,
ELI WALTON.
